WILLIAM B. THURMAN AND MARK W. HILD, OF STOCKTON, CALIFORNIA, ASSIGNORS TO FIREPROOF WALL COMPANY, OF RENO, NEVADA, A CORPORATION

METHOD OF AND MEANS FOR ATTACHING LATHING TO STUDDING

Application filed September 10, 1927. Serial No. 218,814.

This invention relates to improvements in the building art and particularly to a means for applying and securing plaster board lathing or like lathing to metal studs in the erection of walls of various types for Class A buildings, and is particularly directed towards a fastening means and method in connection with the manner of attaching lathing to the studs as preferably set forth in the Makowski Patent No. 1,579,377, although the present invention can well be directed also to the fastening of metal lathing to the metal studs, as will develop as this description is proceeded with.

The primary objective of the present invention is to produce a method and fastening means for the purpose noted by which the lathing may be rapidly, effectively and securely attached to the studding, working solely from the front plane of the wall so that the entire mounting of the lathing may be accomplished with a minimum amount of expense of time, labor and material.

These objects we accomplish by means of such structure and relative arrangement of parts as will fully appear by a perusal of the following specification and claims.

In the drawings similar characters of reference indicate corresponding parts in the several views:

Fig. 1 is a perspective view in section of a fragmentary portion of a stud and piece of plaster board lathing showing the fastening element in the position it assumes when the several elements are all secured together.

Fig. 2 is a sectional view through the studding and lathing showing the fastening element projecting into position ready for the fastening prongs to be cinched together to secure the several parts firmly together.

Fig. 3 is a view similar to Fig. 2 but showing the first bend of the prong made by the tool in carrying out the fastening operation.

Fig. 4 is a view similar to Fig. 3 showing the next bend made in the prong and which completes the fastening operation.

Fig. 5 is a perspective view of the fastening element.

Fig. 6 is a perspective view of a fragmentary piece of studding and a piece of

metal lathing showing a modified form of fastening element which can be used in connection with our improved method for fastening the metal lathing to the studding.

Fig. 7 is a perspective view of the type of fastening element shown in connection with Fig. 6.

Fig. 8 is a sectional view of a stud and fragmentary piece of metal lath showing a modified form of fastening element from that shown in Figs. 6 and 7.

Referring now more particularly to the characters of reference on the drawings, the numeral 1 denotes the studding which is of the usual channel shape, and the legs 1a of which have inclined inner surfaces 1b. The numeral 2 designates the plaster board lath which for the purpose of carrying out our improved method is provided with a longitudinal slot 3 at various points in its width and length at which the lath is to be secured against the studding. In a great many cities ordinances provide that lathing of this type shall be secured to the studding at approximately every six inches, and the lathing strips in commercial manufacture usually run about six feet long and from twelve to eighteen inches wide, and consequently there would be one of these slots 3 at approximately every six inches throughout the width of the lathing and at spaced longitudinal intervals approximating the distance between the studs used in the erection of the wall. By this means the lathing could be applied to the studding as taught in the Makowski patent above mentioned, and the length of the slots would be such as to at all times present a slot transversely across a stud to permit of the insertion and securing of the fastening element, which is constructed and applied substantially as will now appear.

The fastening element comprises a flat member 4 having a pair of projecting prongs 5 and 6 extending at right angles thereto and substantially midway thereof, and preferably formed by stamping it out of the same sheet metal as that of which the element 4 is made. The width of the element 4 is greater than the width of the slot 3 so that when the fastening element is positioned this flat member

will engage the lath 2 on both sides of the said slot 3 with the prongs projecting through the slot.

In practice to secure the lathing in place against the studding the fastening element is first placed in a tool 7 with the prongs 5 and 6 fitted between the jaws 8 and 9 of the tool. The jaws of the tool and the prongs are then projected through the slot 3 so that the prongs fit on each side of the studding 1. Pressure on the handles of the tool 7 causes the jaw 8 to press the prong 5 into frictional engagement with the flat side of the studding, while a dog 9a on the jaw 9 first bends the prong 6 into substantially the position shown in Fig. 3. This brings the upper end of the prong 6 into frictional engagement with the bottom of the channel of the studding as at 6a, and then with this point and the outer corner edge 6b of the outer channel leg 1a as fulcrum points, a continued movement of the jaw 9 of the tool inwardly of the channel causes the prong 6 to be drawn into the position shown in Fig. 4, the frictional drawing action between the points 6a and 6b tending to draw the flat member 4 tightly against the front face of the lathing. Also this action draws the prongs 6 over the inclined surface 1b of the adjacent leg 1a of the studding, and this causes a wedging and drawing action which accentuates the proposition of tightly drawing the lathing, the studding and the fastening element into very close frictional engagement, one with the other to insure absolute rigidity of the lathing relative to the studding after the fastening operation is completed.

The same general idea of fastening metal lathing to the studding is shown in Figs. 6 and 7, but a plain wire clip 10 can be used in this instance, as the flat portion 4 is not necessary in connection with the metal lathing, since the fastening element can be passed through and around one of the loops of the expanded metal lathing.

In Fig. 8 we show how one prong of the element 10a may be bent behind the stud as at 10b if such fastening is deemed advisable.

From the foregoing description it will be readily apparent that we have here shown and claimed a method and means for accomplishing the fastening of the lathing to studding in a very simple and efficient manner, and working only from the front of the wall, and involving a minimum expense of time, labor and material, as is quite essential in erecting walls in a commercial way.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not

form a departure from the spirit of the invention, as set forth herein.

Having thus described our invention what we claim as new and useful and desire to secure by Letters Patent is:

The method of securing together a stud, a plaster lath having a longitudinal slot cut therein, and a fastening element consisting of a flat member having a pair of prongs projecting therefrom, comprising laying the lath against the stud with the slot crossing the stud, moving the prongs through the slot and one on each side of the stud and the flat of the fastening element against the face of the lath, and then applying an instrumentality from the front of the lath through the slot to each of the prongs and pinching them into frictional engagement with the stud.

In testimony whereof we affix our signatures.

WILLIAM B. THURMAN.
MARK W. HILD.
